DESIGN FOR A DISPLAY CONTAINER

William R. Tuttle and Charles W. Stickel, Rochester, N. Y., assignors to The Kurlash Company, Inc., Rochester, N. Y., a corporation of New York

Application May 29, 1940, Serial No. 92,690

Term of patent 14 years

To all whom it may concern:

Be it known that we, William R. Tuttle and Charles W. Stickel, citizens of the United States of America and residents of Rochester, county of Monroe, State of New York, have invented a new, original, and ornamental Design for a Display Container, of which the following is a specification, reference being had to the accompanying drawing, forming part thereof.

In the drawing:

Figure 1 is a perspective view of a display container showing our new design open.

Figure 2 is a rear elevational view thereof showing our new design open.

Figure 3 is an end elevational view thereof taken from the right side of our display container.

Figure 4 is a rear elevational view showing our display container closed.

Figure 5 is a side elevational view taken from the right side of our display container showing it closed.

We claim:

The ornamental design for a display container, as shown.

WILLIAM R. TUTTLE.
CHARLES W. STICKEL.
